DESIGN FOR A CASING FOR A CORN POPPING APPARATUS

Charles J. Cretors, Highland Park, Ill.

Application October 23, 1944, Serial No. 115,924

Term of patent 7 years

(Cl. D52—2)

To all whom it may concern:

Be it known that I, Charles J. Cretors, a citizen of the United States and a resident of Highland Park, county of Lake, and State of Illinois, have invented a new, original, and ornamental Design for a Casing for a Corn Popping Apparatus, of which the following is a specification, reference being had to the accompanying drawing, forming a part thereof, in which Fig. 1 is a perspective

view of a casing for a corn popping apparatus embodying my new design, Fig. 2 is a view in side elevation of the casing and Fig. 3 is a top plan view of the casing.

I claim:

The ornamental design for a casing for a corn popping apparatus, substantially as shown.

CHARLES J. CRETORS.
